UNITED STATES PATENT OFFICE.

DENNIS J. EASLEY, OF PONDER, TEXAS.

COTTON-PICKER'S RECEPTACLE.

1,120,139.

Specification of Letters Patent.

Patented Dec. 8, 1914.

Application filed March 22, 1913. Serial No. 756,146.

To all whom it may concern:

Be it known that I, DENNIS J. EASLEY, a citizen of the United States, residing at Ponder, in the county of Denton and State 5 of Texas, have invented certain new and useful Improvements in Cotton-Pickers' Receptacles, of which the following is a specification.

My invention relates to a new and useful 10 cotton picker's receptacle, and its object is to save time in picking cotton and to render such work less arduous by providing a special form of receptacle to be secured upon the wrist of the cotton picker, said receptacle being so formed as to constitute a convenient receptacle for several handfuls of cotton, the relation of the receptacle to the hand being such that a slight motion of the fingers will deposit a handful of cotton in 15 20 the receptacle.

A further object of the invention is to provide a device of the character described that will be strong, durable, simple and efficient and comparatively easy to construct.

With these objects in view, my invention 25 has relation to several novel features of the construction and use, an example of which is described in the following specification, and illustrated in the accompanying drawing, wherein:

Figure 1 is a perspective view showing the manner in which the receptacle is to be mounted upon the wrist of the cotton picker. Fig. 2 shows the form of the receptacle when 30 flattened out.

Referring now more particularly to the drawing, wherein like reference characters designate similar parts in both the figures, the numeral 1 denotes a flexible sheet-like 40 member, preferably of two thicknesses of material held together by rows of stitching as indicated at 2. The member is formed with opposite arcuate edges 3 and 4.

When the member is mounted upon a 45 wrist as shown in Fig. 1, the peculiar form of the edges 3 and 4 causes the member to assume a funnel shape and become a receptacle, the small end of the funnel being contiguous with the wrist of the wearer and the 50 mouth or larger end inclosing the hand.

Any suitable means may be employed to secure the member to the wrist of a cotton picker but the preferred means will be an ordinary glove fastening such as is shown in the drawings at 5. It will be observed that 55 when this device is in use, an aperture, the edges of which are indicated at 6 in Fig. 1, is produced opposite the back of the wearer's hand. Since it is not intended that any cotton should be accumulated in the receptacle at the back of the wearer's hand, this portion may be open, thus economizing material and decreasing the heating effect of the receptacle upon the hand.

Ordinarily when cotton is being picked by 60 hand, as soon as the picker has gathered a few bolls, he must thrust his hand into the sack to deposit the cotton therein. The frequency of this motion in cotton picking soon becomes wearisome so that the work 65 becomes arduous to the cotton picker. By the use of the above-described device, this motion need be made much less frequently than is possible without said device. It is to be observed moreover that the cotton 70 picker who employs the above described device will constantly have his fingers entirely free thus enabling him to work more efficiently. In the course of a day, a much larger amount of cotton may be picked by a 75 person using the above described receptacle 80 than is possible if such a device is not employed.

The invention is presented as including all such modifications and changes as properly 85 come within the scope of the following claims.

What I claim is:

1. A cotton picker's receptacle comprising a member shaped to fit snugly around the 90 wearer's wrist at one end and flaring outward toward the other end.

2. A cotton picker's receptacle adapted to fit the wrist of the wearer and flared outward around the wearer's hand, said receptacle having a cut out portion over the back of the wearer's hand adapted to permit movement of the latter. 95

3. A cotton picker's receptacle having provision for fastening about the wrist of 100

the wearer and flared outward around the hand of the wearer and forming a pocket under the wearer's hand, said receptacle having a cut-away portion over the back of
5 the wearer's hand of sufficient size to permit free movement of the hand in the receptacle.

In testimony whereof I have signed my name to this specification in the presence of two subscribing witnesses.

DENNIS J. EASLEY.
